CLAIM

The ornamental design for a housing for mounting, arranging and securing electrical power lines to a computer, as shown and described.

DESCRIPTION

FIG. 1 is a left side perspective view of a housing for mounting, arranging and securing electrical power lines to a computer, showing my new design;

FIG. 2 is a top perspective view showing an open position thereof;

FIG. 3 is a front perspective view thereof;

FIG. 4 is a rear perspective view thereof;

FIG. 5 is a left side, top and front perspective view thereof; and,

FIG. 6 is a right side, top and front perspective view thereof. The undisclosed bottom view of the housing is unornamented.
